UNITED STATES PATENT OFFICE

2,415,519

IGNITION DEVICE FOR OIL BURNERS

James E. North, Warrenville, Ill., assignor to
 Sears, Roebuck and Co., Chicago, Ill., a corpora-
 tion of New York

Application October 11, 1943, Serial No. 505,769

1 Claim. (Cl. 126—1)

1

This invention relates to igniting means for oil burners and it is particularly designed for use in combination ranges which include oil burners and gas burners and are therefore equipped with fuel supply means providing both oil and gas.

One object of the invention is to provide new and improved ignition means for an oil burner.

Another object of the invention is to provide an arrangement for lighting an oil burner by means of a gas flame together with means for lighting the gas flame from a point remote from the gas burner itself.

More specifically, it is an object of the invention to provide means for lighting the oil burners of a combination range by employing the continuously burning gas pilot which is located in the range remote from the oil burners and providing a flash tube leading from the pilot to a point adjacent a gas burner which in turn will direct the flame toward the oil burner to ignite it.

Other objects and advantages of the invention will appear from the following description taken in connection with the drawing, in which

The sole figure is a diagrammatic perspective view indicating the general arrangement of igniting means embodying this invention as installed in a combination range.

While there is shown and described herein certain specific structure embodying the invention, it will be manifest to those skilled in the art that various modifications and rearrangements of the parts may be made without departing from the scope of the invention and that the same is not limited to the particular forms herein disclosed, except insofar as indicated by the appended claim.

Referring first to the figure, it may be understood that the broken outlines 1 indicate diagrammatically the general form of the outer casing or walls of a combination range. Four gas burners 2 are shown located in the top of the range and serviced by a gas-fed pilot light at 3, the supply pipe for the pilot being shown at 4 branching from the gas supply pipe 5. At any convenient location within the casing 1 there is provided an oil tank 6 with a supply pipe 7 connected to feed pipes 8 and 9, each having a control valve 10; said pipes lead respectively to the two oil burners 11 and 12 located in one end of the casing 1. These burners are of the conventional type including a plurality of spaced concentric cylinders and provided with annular wicks disposed between certain of said cylinders but not appearing in the figure. Such burners can be started by means of a lighted taper thrust down into the burner structure and in some cases

2

the outer cylinders are tilted upwardly to give access to the wicks, but such methods are inconvenient and tend to produce offending odors and fumes. Accordingly the figure shows a gas burner 13 located inside the oil burner structure at a suitable position for igniting the oil by means of a small gas flame. The gas burners 13 are fed from a pipe 14 which is connected directly to the gas feed pipe 5 and controlled by a valve 15 of the push-button type which is normally closed by a spring but opened for a limited period by pressure on the exposed button 15a of the valve fitting.

In addition to the gas burners 13, the figure 15 shows a branch pipe 16 leading from the pipe 14 and supporting a double burner 17 having jets directed respectively toward the oil burners 11 and 12. The pipe 16 also supports a bent tube 18 terminating in a mixing nozzle 19 which is spaced 20 from the end of a flash tube 20 so as to feed an explosive mixture into the tube when the valve 15 is opened. This mixture flows through the tube 20 which leads to a point adjacent the pilot light 3 in the top of the stove and the mixture 25 of air and gas in the tube 20 is then ignited and flashes back through the tube 20 to ignite the gas at the tips of the double burner 17. The tongues of flame projected in opposite directions from the burner 17 then ignite the gas flowing 30 from the burners 13, 13 within the oil burner structures and these burners in turn light the oil burners. All this takes place in the course of a few seconds and since the pilot light 3 is kept burning continuously, the oil burners 11 and 12 may thus be lighted almost instantaneously at 35 any time when their use is desired. It will be understood that immediately upon the release of the valve button 15a, the gas valve 15 will be closed, cutting off the further supply of gas and thus extinguishing the gas flames at the burners 13 and 17.

In order to insure the propagation of the flame through the flash tube from the pilot 3 to the gap between the end of the tube and the feed nozzle 19, it has been found desirable to provide the tube 20 with a series of holes 21. As the flame travels back from the pilot 3 through the tube, the resulting products of combustion are swept ahead and tend to accumulate in the tube 20 so as to 45 smother the flame before it reaches the lower end of said tube. The holes 21 permit these burned gases to escape from the tube so that they do not 50 impede the progress of the flame therein. The nozzle 19 is of substantially standard construction and includes intake ports 22 for primary air

which is entrained by the flow of gas from the pipe 18 and is therefore fed into the flash tube 20 with the gas itself. Additional air is entrained by the flow from the nozzle into the open end of the tube 20 and some of the air already in the tube will obviously become intermingled with the gas as it rises toward the pilot light so as to produce a readily combustible mixture by which the flame is carried back for igniting the gas at the burner 17.

I claim:

In a combination range which includes a pair of oil burners, an oil supply pipe therefor and a gas supply pipe, a gas jet burner disposed between the oil burner structures with jets directed at both of them, a continuously burning gas pilot remote from the oil burners, a flash tube extending from said pilot burner to a point adjacent the gas jet burner, a gas feed nozzle directed into the end of said tube adjacent the gas jet burner, and a pair of additional gas burners disposed respec-

tively within the oil burner structures, together with valve means arranged to connect the gas supply pipe to said nozzle and to said jet burner and to said additional gas burners simultaneously.
